UNITED STATES PATENT OFFICE

SYDNEY C. KAYES, OF BROCKTON, MASSACHUSETTS, ASSIGNOR TO MONTELLO HEEL COMPANY, OF BROCKTON, MASSACHUSETTS, A CORPORATION OF MASSACHUSETTS

LIFT FOR SEPARATELY-FORMED ATTACHABLE HEELS

Application filed January 31, 1930. Serial No. 424,780.

The object of this invention is to provide, as a member of a separately formed attachable heel, a lift inexpensively made from a box-toe skiving. Such skiving, as is well known, has a relatively long curved edge and a shorter edge intersecting the ends of the longer edge. The thickness of the skiving gradually decreases from the said edges to the central portion, the edges being of substantial and uniform thickness and each of substantially the same thickness as the other, and the central portion being much thinner than the edge faces. A box-toe skiving is a waste product which has been utilized heretofore in the manufacture of heel rands, but not for operative heel lifts.

My invention consists in a blank characterized as above stated, and further characterized as hereinafter stated so that it is convertible into an operative heel lift having a continuous breast edge and a heel-shaped marginal edge, and hereinafter referred to as a skiving lift.

Of the accompanying drawings forming a part of this specification,—

Figure 1 shows in perspective a skiving before it is prepared for conversion into an operative heel lift.

Figure 2 is a section on line 2—2 of Figure 1.

Figure 3 is a section on line 3—3 of Figure 1.

Figure 4 shows the skiving prepared for conversion into an operative heel lift.

Figure 5 shows the prepared skiving connected with an operative lift having a continuous breast edge and a heel-shaped marginal edge.

Figure 6 is an edge view of a heel blank or body which includes a plurality of skiving lifts, looking toward the breast end.

Figure 7 is an edge view of the heel blank or body shown by Figure 6, looking toward one of the longer marginal sides.

Figure 8 is a side view of an assembly which includes a single skiving lift forming the concave heel seat side of cup of a heel base.

Figure 9 is an edge view of the assembly shown by Figure 8, looking toward the breast.

Figure 10 is a section on line 10—10 of Figure 8, showing the concave heel seat before it is completed.

Figure 11 is a view similar to Figure 10, showing the concave heel seat extended to and through the breast edge by a gouging operation.

The same reference characters indicate the same parts in all of the figures.

Figures 1, 2 and 3 show in perspective and in section a leather box-toe skiving having a relatively long edge 15, whose curvature is pronounced, and a shorter edge 16, which may have a slight curvature, said edges being of substantial and uniform thickness, the thickness of the skiving gradually decreasing to the central portion thereof, as shown by Figures 2 and 3.

To prepare the skiving for conversion into an operative heel lift I remove a portion of the skiving by cutting a tapering or V-shaped recess 13 therein, said recess having non-parallel joint-forming edges 14, converging from a wide mouth on the edge 16 to an apex spaced from the longitudinal center of the edge by a flexible neck portion, as shown by Figure 4, said portion flexibly connecting two wing portions of the blank. The shorter edge 16 is partly removed by the cutting operation, so that only the end portions of said edge remain, said portions constituting the parts 16^a of a two-part continuous breast edge. In the skiving thus prepared, the edge 15 has a curvature differing from that of an operative heel lift.

The prepared skiving is now a convertible heel lift blank, and is adapted to be conformed and cemented to an ordinary lift 18 by superimposing it upon the latter and abutting the recess edges 14 together. This operation changes the curvature of the edge 15, so that it registers with the marginal edge of the lift 18, and brings together the breast edge parts or sections 16^a, so that they collectively constitute a continuous breast edge, as indicated by Figure 5. Said breast edge may be trimmed to the form shown by full lines in Figure 5, either before or after the blank is conformed and cemented to the lift 18 and becomes an operative skiving lift.

In forming the recess 13 I cut notches 13^a in the edges 14, near the closed end of the recess, to facilitate the conformation of the convertible blank to the lift 18.

5 The described skiving lift may be utilized in building up a cheap heel body composed of a plurality of skiving lifts and a plurality of ordinary lifts 18, said lifts alternating, as shown by Figures 6 and 7. The lifts 18 may 10 be of substantially the same thickness as the edges 15 and 16^a of the skiving lifts.

15 The heel body may be subjected to powerful compression to render its opposite side surfaces substantially parallel with each other and provide a cheap heel blank or body of the "pancake" variety.

20 Figures 8, 9, 10 and 11 show the skiving lift as an element of a heel base which includes an ordinary lift 20 to which the skiving lift is cemented. The outer side surface of the skiving lift is thus provided with a concave heel seat 21. When the lifts are first 25 assembled, the seat 21 is concave from the rear edge to the breast edge formed by the edge parts 16^a, said parts having their original thickness which is sufficient to permit the formation of an extension 21^a of the seat 21 by a gouging operation.

30 The area of said extension is indicated by dotted lines in Figures 8 and 9, and the formation thereof reduces the thickness of the central portion of the breast edge formed by the parts 16^a, so that the concave heel seat 35 extends through the breast edge of the skiving lift.

I claim:

40 1. As an article of manufacture, a heel lift blank made from a box-toe skiving and convertible into an operative heel lift, said blank having a curved marginal edge, and a breast edge, the outer breast corners of said blank being a greater distance apart than when the blank is formed into a heel lift, the thickness of the blank gradually decreasing from 45 said edges to the center, a portion of the blank being cut out to form a V-shaped recess having a wide mouth leaving two spaced apart sections extending from the heel end to the breast edge, each of said sections converging widthwise from the breast toward the heel end, and at the breast, said sections being of such width so that when brought together, the breast corners of the blank will approximately coincide with the respective breast corners of the heel lift into which the blank is to be formed.

50 2. A heel comprising a plurality of conventional heel lifts, additional heel lifts interposed between and secured to said first 55 mentioned heel lifts, each of the second mentioned heel lifts comprising a blank made from a box-toe skiving and convertible into an operative heel lift, said blank having a curved marginal edge, and a breast edge, the outer breast corners of said blank being a

greater distance apart than when the blank is formed into a heel lift, the thickness of the blank gradually decreasing from said edges to the center, a portion of the blank being cut out to form a V-shaped recess 70 having a wide mouth leaving two spaced apart sections extending from the heel end to the breast edge, each of said sections converging widthwise from the breast toward the heel end, and at the breast, said sections being of such width so that when brought together, the breast corners of the blank will approximately coincide with the respective breast corners of the heel lift into which the blank is to be formed.

75 In testimony whereof I have affixed my signature.

SYDNEY C. KAYES.
